Primary Examiner — Paula Greene(74) *Attorney, Agent, or Firm* — Michael J. Feigin, Esq.; Feigin & Fridman(57) **CLAIM**

The ornamental design for the earbud, as shown and described.

DESCRIPTION

FIG. 1 shows a bottom and side perspective view of the earbuds.

FIG. 2 shows a top and reverse side perspective view thereof.

FIG. 3 shows a side elevation view, the reverse side being a mirror image thereof.

FIG. 4 shows a top plan view thereof.

FIG. 5 shows a bottom plan view thereof.

FIG. 6 shows a front elevation view thereof; and,

FIG. 7 shows a rear elevation view thereof.

The broken lines depict environment that forms no part of the claimed design.
